(57) **CLAIM**

We claim the ornamental design for a three-cell beverage box, as shown and described.

DESCRIPTION

FIG. 1 is a rear perspective view of a three-cell beverage box showing the claimed design with a top portion positioned in an open configuration and a telescoping portion positioned in a retracted configuration.

FIG. 2 is a rear elevation view thereof.

FIG. 3 is a front elevation view thereof.

FIG. 4 is a left-side elevation view thereof.

FIG. 5 is a right-side elevation view thereof.

FIG. 6 is a top plan view thereof.

FIG. 7 is a bottom plan view thereof.

FIG. 8 is a plan view of the three-cell beverage box shown in a fully collapsed configuration.

FIG. 9 is a rear perspective view of the three-cell beverage box shown in a partially collapsed configuration.

FIG. 10 is a front perspective thereof.

FIG. 11 is a rear elevation view of the three-cell beverage box with the top portion positioned in the open configuration and the telescoping portion positioned in an extended configuration; and,

FIG. 12 is a rear perspective view of the three-cell beverage box with the top portion positioned in a closed configuration and the telescoping portion positioned in the retracted configuration.

Those features shown in broken lines, such as the broken lines denoting lines of weakness shown in FIGS. 1–5 and 8–12, form no part of the claimed design.
